UNITED STATES PATENT OFFICE.

JOSEPH FRASER, OF PARNELL, AUCKLAND, NEW ZEALAND.

BIN FOR HOLDING FLOUR, SUGAR, AND THE LIKE.

1,253,581.

Specification of Letters Patent. Patented Jan. 15, 1918.

Application filed August 21, 1915. Serial No. 46,679.

To all whom it may concern:

Be it known that I, JOSEPH FRASER, a citizen of the Dominion of New Zealand, and residing at Cowie Road, Parnell, Auckland, in the Provincial District of Auckland, in the Dominion of New Zealand, have invented certain new and useful Improvements in Bins for Holding Flour, Sugar, and the like, of which the following is a specification.

This invention relates to bins employed for holding flour, sugar, grain and many other products which can be stored in bins, the object of the invention being to provide a bin from which the contents may be withdrawn in the order in which they were placed therein thus preventing waste by insuring that a remoter supply shall be used before a more recent supply. The bin is supported without contact with a wall or floor, thereby keeping it free from injury by damp or vermin.

The bin is hung so that it can be oscillated and has a lid at the top and at the bottom is curved forwardly and upwardly where a lid is provided for the removal of the contents. Near the bottom of the bin, an agitator is provided and is operated by oscillating the bin for the purpose of loosening the contents which may have jammed in the bin.

The drawing herewith illustrates the invention:—

Figure 1, is a side elevation of a bin.

Fig. 2, is a front elevation of a pair of bins partly in section.

Fig. 3, is an elevation of the bracket, and

Fig. 4, is a plan of a bracket with a trunnion in position.

The bin consists of a rectangular and tapering body 1 that is to say, the thickness from front to back of the body is less at the top than at the bottom. The upper end of the body is closed by a lid 2, and the bottom thereof terminates in a curved formation or discharge well 3 which extends forwardly of the front of the bin and for a distance upwardly of the same.

The lower part 4 of the front of the bin dips into the well 3. The top of this well 3 is closed by a lid 5.

Near its top, the bin 1 is provided with trunnions 6 having heads 7 and journaled in brackets 8 fixed to battens 9. The side of the bracket is engaged between the head 7 and the base 8^a of the trunnion. The battens are carried in brackets 10 and 11 which

have sockets 12 in which the battens 9 are secured by screws 13.

The brackets 10 and 11 are fixed to a wall 14 or other desired support by screws 14^a.

Near its lower end the body 1 is provided with an agitator consisting of a spindle 15 to which radial arms 16 are fixed. The spindle is mounted in brackets 17 and 18 fixed to the sides of the body 1, the brackets 17 being large enough to close a hole 18^a 65 through which the agitators may be introduced into the bin. One end of the spindle 15 is provided with an arm 19 having a slot 20 which engages a pin 22 projecting from the batten 9. The pin 22 is adjustable in height upon the batten 9 in order to regulate the stroke of the agitator.

A bar 23 unites the bottoms of the battens 9 and the heads 7 of the trunnions 6 passing into the brackets 8 prevent the battens from spreading at the top.

The lid 2 is provided with a mirror 24, and by raising the lid, the amount of contents of the bin are readily observed by looking into the said mirror when the top 80 of the bin is at too great height for a person to look directly thereinto.

This is more readily done by holding a light and raising the lid sufficiently to reflect the light into the inside of the bin. 85 The quantity of material in the bin is readily ascertained by a scale 25 marked or fixed upon the inside of the bin.

The curve of the bottom of the well 3 and the depth to which the part 4 dips into the 90 said well, are varied to suit the material to be stored in the bin. This part 4 operates as a baffle to control the inflow of the material into the outer part of the well.

A bar 26 fixed across the body 1 is adapted 95 to contact with a buffer 27 fixed to the wall 14. The buffer may be fitted with springs or rubber to absorb shock.

The material to be stored is inserted at the top of the bin after the lid 2 has been 100 raised. Some kinds of material are liable to jam in a vertical bin, but this is prevented by making the body to taper as described. With some materials this taper formation is not sufficient and the agitator is therefore 105 provided. The arms 16 of this agitator may have any desired length, and some arms may be made longer than others, or the tips of the arms may be curved or otherwise formed to bring down the contents of the bin. In 110

all cases the arms or some of the arms have a sufficient length to reach nearly to the side of the bin at the extremity of its oscillation.

In case of the material jamming in the body 1, the bin is oscillated, which action rotates the spindle 15 in its bearings and operates the agitator. The lower part of the contents is set free and the upper part of the same also falls down.

10 The contents are removed from the well 3 by means of a scoop or otherwise, after raising the lid 5.

What I do claim and desire to secure by Letters Patent of the United States is:—

15 1. In a device of the character described, a support, a bin oscillatingly supported thereby provided with an inlet opening at its upper end and a discharge opening at its lower end, an agitator within said bin

20 adjacent its lower end, and means to actuate said agitator as said bin is oscillated.

25 2. In a device of the character described, a support, a bin oscillatingly supported thereby, a rotatable agitator within said bin having bearings journaled in the walls thereof, an arm secured to said agitator and positioned outside of said bin, and means carried by said support and engaging said arm to rotate said agitator as said bin is oscillated.

30 3. A bin, battens upon which the bin is oscillatingly supported, and brackets adapted to be secured to a support and having sockets to receive the battens and hold them against movement.

35 4. A bin provided with trunnions adjacent its upper end, battens provided at the sides

thereof facing the bin with open brackets to receive the trunnions by a downward movement of the bin, and brackets adapted to be secured to a support and upon which the battens are fixedly mounted.

40 5. A bin, battens upon which the bin is supported, and rearwardly extending brackets adapted to be secured to a support and upon which the battens are fixedly mounted, the length of the brackets being such that the bin is held out of engagement with the support.

45 6. A bin provided with trunnions, battens having brackets whereon the trunnions are journaled, brackets supporting the battens, an agitator near the bottom of the bin, a slotted arm on the agitator engaging a pin projecting from the batten, substantially as set forth.

50 7. A bin provided with trunnions having headed outer ends, battens having brackets at the upper ends of the sides thereof facing the bin to receive the trunnions and recessed to receive between themselves and the battens the headed outer ends of the trunnions, a cross bar uniting the lower ends of the battens, and brackets upon which the battens are fixedly mounted and which are adapted to be secured to a support.

55 In testimony whereof I have signed my name to this specification in the presence of two witnesses.

JOSEPH FRASER.
